UNITED STATES PATENT OFFICE.

LYLE E. WILCOX, OF MCLEAN, ILLINOIS.

SIGN-EXHIBITING MEANS.

1,354,638.

Specification of Letters Patent.

Patented Oct. 5, 1920.

Application filed June 3, 1919. Serial No. 301,395.

To all whom it may concern:

Be it known that I, LYLE E. WILCOX, a citizen of the United States, residing at McLean, in the county of McLean and State 5 of Illinois, have invented certain new and useful Improvements in Sign-Exhibiting Means, of which the following is a specification.

This invention relates to station indicators for passenger cars and more particularly to an improved mechanism especially adapted to be mounted upon railway cars for indicating the stations of street stops so that the passengers within the car may observe the names of the stations which will appear in proper order as the car advances from one station or street to another.

One of the objects of the invention is to provide an improved mechanism of this 20 character which will automatically operate through the medium of suitable tripping devices arranged in the vicinity of the station, and which will be actuated by the rotary movement of the axle on one of the trucks 25 of the car.

The invention further aims to provide an apparatus of this character which may be readily adapted for mounting on any type of railroad car or street passenger car without altering any of the parts thereof.

A further object of the invention is to provide an indicator of this character which may be operated to properly indicate the stations regardless of the direction of movement of the car thereby assuring proper display of the names of the stations as the car travels from one end of the route to the other and back again.

A further object of the invention is to 40 provide a device of this character which consists of comparatively few parts and is simple in construction, but durable and well adapted to withstand the rough usage to which devices of this character are ordinarily subjected.

For a full description of the invention and the advantages and merits thereof, reference is to be had to the following description and accompanying drawings, in which:—

Figure 1 is a vertical fragmentary section through a car showing my invention applied thereto.

Fig. 2 is a section taken substantially on 55 the line 2—2 of Fig. 1.

Fig. 3 is a section taken on the line 3—3 of Fig. 2.

Fig. 4 is a detailed view of the slotted end of one of the shaft hangers.

Most of the mechanism is arranged beneath the floor of the car A and is adapted to be actuated by the axle B on one of the trucks of the car. This axle is provided with a friction disk 1 having a beveled edge adapted to be engaged by a second friction 60 disk 2, the beveled edge of which is adapted to engage the beveled edge of the disk 1 at a proper interval. The disk 2 is secured to a shaft 3 at one end thereof, the shaft being equipped at its opposite end with a gear 4 65 in mesh with a gear 5 on a parallel shaft 6. The end of the shaft 6 is provided with a beveled gear 7 in mesh with the beveled gear 8 on the lower end of the vertical shaft 9 which extends upwardly through the car 70 body and is adapted to drive the sign displaying mechanism in a manner that will 75 hereinafter appear.

Attached to the car floor is a sleeve 10 within which one end of a trip 11 is slidably 80 received, the interior of the sleeve 10 being provided with a coil expansion spring to normally urge the trip rod 11 downwardly. The lower end of the trip rod 11 is provided with a shoulder 12 which will rest against 85 the abutment member 13 when the trip rod is in normal position and forced outwardly by the spring. The lower terminal of the trip rod carries a wheel 14 which is adapted to engage and ride upon a trip rail 15 arranged at the side of and parallel with the railway rail. One of these trip rails 15 is provided adjacent each station or street crossing at which the car ordinarily stops so that the mechanism will be actuated 90 whenever the wheel 14 engages one of the trip rails 15. It will be noted that the top of the trip rail is slightly above the top of the railway so that the trip rod 11 will be raised the required distance when it engages 95 100 the trip rail.

One end of a clutch shaft lever 16 is joined to the trip rod as indicated at 17 and this lever 16 is pivotally supported on the pin 18 which is carried by a supporting 105 member 19. The opposite end of the lever 16 forms a right angularly extending arm 20 the terminal of which receives the shaft 3 upon which the friction clutch disk 2 is mounted. Fig. 4 shows the manner in which 110

the shaft 3 is suspended in position, the hanger 21 having its lower end provided with a slot 22 in which the shaft 3 is received for the purpose of permitting the shaft 3 to move whereby the friction disk 2 may be engaged or disengaged with the friction disk 1. In this connection it should be pointed out that only a fraction of an inch movement is required to disengage the 10 friction disks 1 and 2 and since the shaft is relatively long the engagement and disengagement of the disks 1 and 2 may be accomplished without difficulty and still maintain the gears 4 and 5 in mesh.

15 A counter shaft 23 is suspended from hangers 23' and is arranged parallel with the shaft 3 but slightly below the same as shown to advantage in Figs. 2 and 3 of the drawing. The end of this shaft 23 carries a 20 gear 24 in mesh with an idler 24' which meshes with gear 4 so that the two shafts 3 and 23 turn in the same direction. A cam 25 is mounted upon the shaft 23 and a similar cam 25' is mounted upon the shaft 25 3 and as shown clearly in Fig. 3 these cams project in opposite directions. Extending vertically and projecting between the cams is a movable bar 26, the upper end of which is provided with a hingedly mounted abutment member 27 adapted to be engaged by the cam 25'. A second abutment member 28 is mounted below the member 27 and is adapted to be engaged by the cam 25 the 30 two members being hingedly mounted so that they will rise when either of the cams strike them from the bottom but will cause the bar 26 to be forced downwardly when either of the cams strike them from the top. This bar is movable through a bracket member 29 projecting from a support 30 and the 35 lower end of the latter has pivotally connected thereto a bell crank lever 31 one end of which is adapted to engage the lower end of the movable bar 26 while the other end is joined to a locking rod 32. The bracket member 29 is provided with a bearing 33 which supports the rod 32 and which acts as an abutment for a coil expansion spring 34, the opposite end of which engages an 40 abutment 35 fixed to the rod 32 whereby the rod is moved toward the trip member 11. At the proper point, the trip rod 11 is provided with a notch 36 which receives the end of the rod 32 as shown. It should be understood that the parts as shown in the drawings are in the position they assume when the trip rod is raised by virtue of its engagement with the trip rail 15. A brake 45 is provided for preventing the parts from moving after each actuation of the mechanism and this brake comprises the arm 37, connected as shown to the trip rod 11 and having its opposite end pivotally mounted as indicated at 38 on a support 39, the arm 37 carries a brake shoe 40 normally above the shaft 6 so that the brake shoe will move into engagement with the shaft 6 when the arm swings downwardly by virtue of the movement of the trip rod 11 when rod 32 disengages the notch 36. Conveniently located within the car A is a casing 41 within which is arranged the parallel shafts 42 and 43 having rollers 44 around which is wound the flexible carrier having the names of the stations or streets printed thereon. The 50 shaft 43 has one end provided with a beveled gear 45 adapted to be engaged by either of the beveled gears 46 and 47 on the upper end of the shaft 9. These gears are mounted upon a sleeve 48 which is slidably mounted upon the shaft 9 but is provided with a suitable key or the like whereby rotary movement is imparted to the gears when the shaft is turned, while at the same time the sleeve is free to be adjusted longitudinally for moving the gears 46 and 47 into and out of engagement with the gear 45. This movement is accomplished by a pivoted lever 49 having one end engaged with the sleeve 48 and its opposite end connected to 55 a cable 50 which may be actuated by the conductor, within the car.

Assuming that the rod 32 is disengaged from the notch 36 and that the trip rod 11 is in its lowermost position, and the car is 60 approaching a station. When the wheel 14 strikes the trip rail 15 it will be raised to the position shown and the upward movement of the trip rod 11 will cause the lever 16 to be actuated for moving the shaft 3 to cause 65 the friction disks 1 and 2 to engage for actuating the shaft 3 and thereby actuating the shafts 6 and 23 through the intermeshing gears 4, 5, 24 and 24'. This movement of the shaft 6 imparts movement to the shaft 7 through the medium of the gears 8 and 9 so that the sign displaying mechanism in the 70 casing 41 is actuated so that the carrier will be moved to display the name of the next succeeding station. The cam 25 will then 75 have moved sufficiently to engage the abutment member 27 thereby forcing the bar 26 downwardly to actuate the bell crank lever 31 whereupon a pull is exerted on the rod 32 for disengaging the end of the rod from 80 the notch 36 thereby permitting the spring to force the trip rod 11 downwardly whereupon the parts assume their normal position, the friction disks being out of engagement and ready for the actuation which will 85 occur at the next station. This operation is repeated as the car travels from one station to another so that the names of the stations will be displayed in their proper order. Now, when the car reaches the end of the 90 route it will be obvious that the names must appear in the reverse order and since the axle will rotate in the opposite direction, the movement imparted to the shaft will also be 95 opposite. The actuation of the device is 100

thereby the same except for the action of the cam member 25 on the abutment member 28. Since the shaft 23 will be rotated in the opposite direction it will be obvious that 5 this cam will actuate the bar 26 while the cam member 25' will engage the lower face of the abutment member 27 causing it to swing on its hinge whereby the cam 25' may pass without injuring the mechanism. 10 It will be obvious that this arrangement permits the change to be entirely automatic and, if for any reason it is found necessary to move the car backwardly and forwardly at any point along the route, the action of the 15 mechanism will maintain the station indicating means in the proper order and the car may move backwardly and forwardly between stations without requiring any alteration in the mechanism and the order 20 of appearance of the names will be thereby always corrected.

When the mechanism is employed on a car traveling over a belt line or one having a loop at its terminal, it will be obvious that 25 the change cannot be accomplished by the reverse movement of the car consequently I have provided the member 50 which may be pulled by the conductor or operator of the car to change the gears 46 and 47 for engaging or disengaging the gear 45 thereby changing the direction of rotation of the shaft 43 for reversing the movement of the flexible carrier on which the station names are printed.

35 The foregoing description and accompanying drawings have reference to what might be considered to be the preferred or approved form of my invention. I desire it to be understood that I may make such 40 changes in the construction, combination and arrangement of parts, material, dimensions, et cetera, as may prove expedient and fall within the scope of the appended claims.

Having thus fully described my invention 45 what I claim as new and desire to secure by Letters Patent, is:—

1. A station indicator for cars including a sign exhibitor operable from the car axle, means for clutching up the exhibitor with 50 the car axle including a trip device engaging station stops, a locking rod for holding the trip inoperative, a member having

hingedly mounted abutment portions connected to said rod and oppositely projecting cams arranged to alternately operate 55 upon said member for releasing said rod.

2. An actuating mechanism for an indicator including a fixed drive shaft, an indicator shaft, a geared, movable clutch shaft extended for movement between the said 60 drive and indicator shafts, a trip device, a bell crank connection between the trip and the clutch shaft for moving the shaft to establish a gear connection upon tripping of the trip device between the said drive shafts 65 and the said indicator shaft, and plunger means for automatically gripping the trip device to hold it in tripped position and cam actuated abutment means on said plunger whereby it may be automatically released 70 from engagement with the trip device.

3. An actuating mechanism for an indicator, including in combination, an indicator shaft, a fixed drive shaft, a movable 75 clutch shaft supported for movement between the said indicator and shaft, with one end geared to the former shaft and the other adapted to be in gear at intervals with the latter shaft, means for bringing said clutch 80 shaft in gear with the drive shaft, said means consisting of a trip device engaging station stops, a trip lock normally operating to hold the trip device inoperative, and an alternating cam mechanism in gear with said clutch 85 shaft for automatically releasing the said shaft for automatically releasing the said trip device upon rotation of the clutch shaft.

4. A station indicator for cars including a sign exhibitor operable from the car axle, means for clutching up the exhibitor with 90 the car axle, and including a trip rod engaging station stops, a brake for said clutch means actuated by said trip rod, said trip rod adapted when moved to alternately operate the clutch means and the brake 95 whereby the latter is applied to the clutch only when the same is disengaged from the car axle.

In testimony whereof I affix my signature in presence of two witnesses.

LYLE E. WILCOX.
